UNITED STATES PATENT OFFICE.

HINRICH KÄHLER, OF HAMBURG, GERMANY.

APPARATUS FOR INDICATING DIRECTION OF ROTATION OF MOTORS.

SPECIFICATION forming part of Letters Patent No. 637,873, dated November 28, 1899.

Application filed April 7, 1899. Serial No. 712,130. (No model.)

To all whom it may concern:

Be it known that I, HINRICH KÄHLER, a citizen of the German Empire, and a resident of Hamburg, Germany, have invented certain new and useful Improvements in Apparatus for Indicating the Direction of Rotation of Motors, of which the following is a specification.

This invention relates to an apparatus for indicating the direction of rotation of motors of all kinds, and particularly of marine engines, thus informing the helmsman whether the engineer has understood and carried out his orders.

15 The apparatus comprises two levers, one of which is connected with the reversing-gear mechanism, while the other is connected to the indicator-rod of the engine. The former is shifted only when the engine is reversed; but the latter is continuously oscillated to oscillate a pair of contact-arms and cause either one or the other of them to make and break contact with the lever connected to the reversing-gear. This will cause either the "backward" or the "forward" indicating mechanism to be set by an electric current, so that the movement of the engine is automatically indicated.

In the accompanying drawings, Figure 1 is 30 a longitudinal section of the apparatus; Fig. 2, an elevation of the indicating mechanism set thereby; Fig. 3, a plan of Fig. 1; Fig. 4, a section on line $x-x$, Fig. 2.

Within the chest a , which is placed near the 35 engine or is affixed to the cylinder, are secured two shafts b and c . The shaft b carries a two-armed lever e , the lower arm of which is connected by rod d to the reversing-gear shaft. In order to permit the connection 40 between the parts d e to be adjusted, they are slotted and connected by a bolt engaging the slots, as shown.

Upon the shaft c are fitted two lever-arms or tappets f f' of equal length, connected to 45 a third lever-arm g , which receives oscillating motion by rod h from the indicator-rod or other mechanism actuated by the piston. The tappets f f' are each placed at an angle of about one hundred and twenty degrees to 50 the arm g and will by motion of rod h be simultaneously rocked. Contact-arms k k' , suspended from bolts i i' between frames m ,

are adapted to make contact with the tappets f f' , respectively, the arms being connected to each other and to the chest by means of 55 springs l . These springs are of equal strength and neutralize mutually their expansion, so that but little power is required to actuate the arms k k' . The arm k is by wire k^3 connected to lamp q in the backward compartment of the indicator. This lamp also connects by wires e' e^2 battery E and wire e^3 with the lever e . The arm k' is by wire k^3 connected to the lamp q' in the forward compartment of the indicator. This lamp also connects by wires e^4 e^2 battery E and wire e^3 with the lever e .

If the motor is going forward, the lever e assumes the position shown in Fig. 1. The arm k' will by the lever g be so rocked that 70 it will alternately make and break contact with the lever e at each stroke of the piston. This will cause a constant glimmer to be diffused through the forward chamber by lamp q' , thus indicating that the engine is going 75 forward. At the command "backward" the lever e is thrown into contact with arm k , and thus the glimmer will be produced by the lamp q in the backward chamber.

The indicating mechanism consists of a case 80 n , divided by partition n' into two chambers and provided with a cover o , having a translucent glass plate p . The chambers inclose the lamps q q' , respectively, which are attached to the bottom plate n^2 of the case. 85 The glass pane p may be provided above the lamps q q' with marks, words, or signs, indicating backward and forward motion, respectively. The cover o turns on a hinge o' and is tightly closed by a screw o^2 .

90 My improved apparatus besides indicating the direction of motion permits the rotation of the engine to be accurately ascertained, and thus serves also as an indicator for the speed of the revolutions.

95 What I claim is—

1. A motion-indicator composed of a pair of contact-arms adapted to be oscillated by a motor, a lever set by the shifting-gear, an indicator, and electric connections between the 100 indicator, lever and contact-arms, substantially as specified.

2. A motion-indicator composed of a pair of pivoted contact-arms, a lever-arm actu-

ated by the piston of a motor, tappets operated by the lever and adapted to oscillate the contact-arms, a lever set by the shifting-gear, an indicator, and electric connections 5 between the indicator, lever and contact-arms, substantially as specified.

3. The combination of a pair of contact-arms adapted to be oscillated by a motor, with a lever set by the shifting-gear, an indicator

composed of a pair of lamps, and electric connections between the lamps, lever and contact-arms, substantially as specified. 10

Signed by me at Hamburg, Germany, this 23d day of March, 1899.

HINRICH KÄHLER.
